UNITED STATES PATENT OFFICE.

CLARENCE D. TRUSSELL, OF POUGHKEEPSIE, NEW YORK, ASSIGNOR TO TRUSSELL MANUFACTURING COMPANY, OF POUGHKEEPSIE, NEW YORK, A CORPORATION OF NEW YORK.

LOOSE-LEAF BINDER.

Application filed April 7, 1920. Serial No. 371,874.

To all whom it may concern:

Be it known that I, CLARENCE D. TRUSSELL, a citizen of the United States of America, residing in Poughkeepsie, in the county of Dutchess and State of New York, have invented certain new and useful Improvements in Loose-Leaf Binders, of which the following is a specification.

This invention relates to temporary binders or those designed for binding together loose leaves in book form. It relates particularly to so-called ring binders, wherein half rings or hooks are adapted to close together to constitute binding means and to open out to permit the removal of the perforated sheets or leaves.

The improvements relate especially to the construction of half rings or hooks, and their carrying plates, and to the construction of aligners or centering pieces which are applied to the top plate of the binder and serve to hold the bound sheets outwardly in engagement with the inner faces of the hooks.

The preferred construction and certain modifications thereof will be described with reference to the accompanying drawings, wherein,—

Figure 1 is a transverse section showing the hooks closed and the book partly filled with loose leaves;

Fig. 2 is a plan showing the book open, with the leaves removed and the hooks separated;

Fig. 3 is a fragmentary plan of the top plate;

Fig. 4 is a fragmentary plan of the hook plates;

Fig. 5 is an elevation of one of the hooks;

Fig. 6 is a perspective of one of the hooks;

Fig. 7 is an enlargement of part of Fig. 4, illustrating the mode of inserting the hooks in the hook plate;

Fig. 8 is a perspective view of one of the aligners;

Fig. 9 is a view similar to Fig. 7, showing a modified construction;

Fig. 10 is a perspective view of the hook shown in Fig. 9;

Fig. 11 is an elevation of a hook;

Fig. 12 is a plan of a modified construction of hook plate, showing the mode of introducing the hook thereinto;

Fig. 13 is a view showing the hook introduced, and

Fig. 14 a similar view showing the parts 55 swaged together, the resulting attachment being shown in Fig. 15 in side view, with the hook plate in cross-section;

Fig. 16 shows a modification of Fig. 3.

In Figs 1 and 2, A designates the book cover, and B as a whole the loose-leaf binding mechanism, which commonly comprises an attaching plate C suitably fastened to the book back, a spring back plate D, a pair of hook plates E, E, and two or more pairs 60 of hooks or half rings F, F, fastened to the hook plates. The hook plates are engaged at their inner or meeting edges, and have a hinge connection with the flanges of the back plate D at their outer edges. All of 65 these parts may be of any usual construction and be substituted by any equivalents known in the art, except with respect to those features hereinafter set forth as constituting necessary parts or elements of the present 70 invention.

One feature of the invention provides a simple and cheap means for attaching the hooks F to the hook plates E. The hook plates are formed with openings or slots, and the hooks are formed with opposite notches; the hooks have their notched ends introduced into the openings in the plates, the two being forcibly united so that portions of the plate enter the notches in the hook with such a tight fit that any displacement of the hooks under practical conditions of use becomes impossible. One suitable construction is that best shown in Figs. 80

2 to 7, inclusive. The hook plates E E are here formed with openings a having each a large portion b to receive the base of the hook, and a narrow portion c to make a tight fit with the notched part thereof. 85

Each hook F is formed preferably of wire 90 elliptical in cross-section, and has, near its end designed for attachment to the plate opposite notches d, leaving beneath these a head e. The enlarged part b of the opening is large enough to freely admit the head 95 e, as shown in Fig. 7, while the narrow portion c of the opening forms a slot barely wide enough to receive the shank of the hook between the notches d. To unite the parts the head e is thrust into the larger part of the opening, and the base of the hook is then forcibly moved to the position shown in dotted lines at f in Fig. 7. The propor- 100

105

2
tions of the parts are such that when thus displaced, the thickness of the plate E is tightly embraced between the sides of the notches *d*; and the neck portion between the notches *d* is tightly embraced in the narrow slot *c*, so that the plate and hook are united with great tightness and firmness. This displacing operation is performed under pressure in a suitable press, or by means of any suitable construction of dies. If the interfitting parts are correctly proportioned, the joint thus made is amply secure without any necessity of swaging or riveting the metal. The described construction is very cheap, and the parts can be assembled with great rapidity.

This construction may be modified, as shown, for example, in Fig. 9; where the opening *a'* in the plate E is of substantially the cross-section of the base *e* of the hook, and the hook is turned at right angles for inserting its base through this opening, whereupon the hook is forcibly given a quarter turn, so that its notches *d* engage the margins of the opening *a'* with the requisite firmness. If desired, the engagement may be tightened by swaging or riveting the head *e*.

With the constructions thus described it is preferable to make the hook of wire, elliptical or approximately so in cross-section. With the constructions shown in Figs. 11 to 15, inclusive, the hooks may be made of round wire.

Fig. 11 shows the hook in side view, and Fig. 12 shows the plate with its opening *a*, which in this case is a slot or notch entering in from one edge. The notched portion of the hook E is presented and introduced as shown in Fig. 12, bringing it to the position shown in Fig. 13, whereupon by a swaging operation the head *e* of the hook is squeezed or riveted into the enlarged part of the opening so as to fill the latter in the manner shown in Fig. 14, the completed structure being shown in Fig. 15.

It will be seen that in each of the forms claimed in my present application the plate has openings which first admit the base-50 portions of the hooks, and these portions are then displaced with respect to the openings, either by moving the hook outwardly (toward the outer or hinge edges of the hook plates) as in Figs. 2, 4 and 7, or by turning the hook at right angles, as in Fig. 9, or by upsetting or swaging the base portion of the hook as in Figs. 12-15. In each case the plate remains unaltered in the process of uniting the hooks, their tight engagement being brought about by a change in the base portion of the hooks; and in each case the plate has solid metal between the opening where the hook is finally fixedly held and its margin at the meeting edge.

65 A further feature of the invention pro-

vides an improved construction of so-called aligner for holding the sheets which are bound into the ring book or loose-leaf binder, in proper position. In ring books of this class it is necessary that the holes in the sheets be much larger than the rings, so that there is considerable play of these sheets on the rings. The purpose of the aligner is to take up this play by holding the sheets outwardly with their holes in contact with the inner faces of the rings, thereby evening or aligning the outer edges of the sheets and preventing that looseness or irregularity of the sheets which is commonly observed in loose-leaf books of this character. The aligners shown at G are essentially round objects located within or adjacent to the extreme rings or pairs of hooks F near opposite ends of the book (or, in the case of books having more than two pairs of hooks, the aligners may be introduced within the intermediate pairs, or between pairs, if desired). While it is not essential that the aligner shall be located directly within the rings or hook pairs, yet this is the preferable construction, although their function will be performed if they are located reasonably near to such pairs. The present invention provides for mounting the aligners upon the usual top plate H. This top plate is usually of the construction shown in cross-section in Fig. 1, having side flanges which embrace yieldingly between them the flanged edges of the spring back plate D, and having lateral notches *h* to receive the hooks F. Such aligners have heretofore been attached to the hook plates E, but by the present invention they are attached to the top plate, which affords a better base for the aligners because it is substantially immovable in use. The preferred construction of the aligners is that shown in Fig. 8, the aligner being punched out of sheet metal and then bent into substantially the form shown. The ends of the strip are brought near to one another and are adapted for connection in any suitable manner with the top plate H. A desirable construction is that shown, wherein the ends of the aligner are formed on opposite sides with notches *i* adapted to engage slots in the top plate. The engagement preferably is accomplished by making the aligner of spring metal, so that its end portions tend strongly to spring toward each other, or away from each other, as may be preferred. In the construction shown in Figs. 1 and 3, they are made to spring toward each other, the slots *j* in the top plate being of the shape clearly shown in Fig. 3, comprising a longer portion *k* just sufficiently long to receive the unnotched ends of the aligner, and a shorter portion *l* to receive the notched end portions of the aligner. The connection is made by springing the ends of the aligner apart sufficiently to pass them through the longer portions *k*

of the slots until their notches *i* are brought into the plane of the plate, whereupon they are released and spring into the shorter portions *l*, as shown. In use, the pressure upon 5 the aligner is inward, so that it does not tend to disturb the connection thus made.

A modified construction is shown in Fig. 16, where a single slot *j'* is formed in the top plate, having its middle portion *k'* 10 longer than its side portions *l'*. The aligner is of the same construction as shown in Fig. 8, but in this case its ends tend to spring outwardly. It is inserted by pressing its end portions together and introducing them 15 through the elongated portion *k'*, and then permitting them to separate, so that their notched portions engage with the shorter portions *l'* of the opening, as indicated in Fig. 16. This construction is suitable if 20 the aligner is made sufficiently stiff so that its outward pressure will keep it in place, notwithstanding the inward pressure of the bound sheets in use.

The connection between the aligner and 25 top plate may be otherwise accomplished in any known or suitable way. The constructions described have the advantage that they do not require any riveting or swaging together of the engaging parts; nevertheless, 30 such riveting or swaging is not inhibited in the practice of my invention.

The described constructions tend to improve the operation and cheapen the manufacture of loose-leaf binders of the ring 35 type. It is to be understood that the invention is not limited to the precise embodiments shown and described, any modification or variance thereof within the scope of the appended claims being within the invention.

What I claim is:—

1. A loose-leaf binder comprising opposed related hook plates and hooks, the 45 plates formed with openings to receive the hooks and the hooks having their base portions notched on opposite sides to engage the marginal portions of said openings, the openings being of size to permit the insertion of the base portions of the hooks through the openings, and the hooks and 50 openings related to admit of a displacement of the base portion of the hooks after such insertion to a final interlocking relation where the parts are in tight engagement, the

plates having at the openings marginal portions preventing outward displacement of the hook bases. 55

2. A binder according to claim 1, the openings in the plates being holes shaped to admit the base portions of the hooks in 60 one position of the latter and to engage the notches therein after displacement of the hooks.

3. A binder according to claim 1, the openings in the plates being holes having each a wider portion and a narrower portion, the wider portions shaped to admit the base portions of the hooks in one position of the latter and the narrower portions shaped to engage the notches in the base 70 portions of the hooks after the displacement of the latter to final position. 75

4. A binder according to claim 3, the holes being narrower on the sides toward the outer edges of the plates, and wider on the sides remote from such edges. 80

5. A loose-leaf binder comprising opposed movable hook plates, hooks fixed to said plates, a top plate covering the hook plates, the latter connected to occupy a fixed relation to said top plate when the hooks are closed, and aligners for the leaves mounted on said top plate, and formed of bent sheet metal, their ends interlocked with openings in the top plate. 85

6. A loose-leaf binder according to claim 5, the openings in the top plate being slots adapted to receive the ends of the aligners, and the latter having portions entering and engaging with such slots. 90

7. A loose-leaf binder according to claim 5, the aligners formed of bent sheet-metal having notched ends, and the openings receiving said notched ends, said openings having narrower portions engaging said notched ends to hold the aligners fixedly in place. 95

8. A loose-leaf binder according to claim 5, the aligners formed of bent resilient sheet-metal having notched ends, and the openings receiving said notched ends, said openings having narrower portions engaging therewith and held in engagement by the resilient stress of the aligners. 100

In witness whereof, I have hereunto 105 signed my name.

CLARENCE D. TRUSSELL.
